US00D532107S

(12) **United States Design Patent** (10) **Patent No.:** **US D532,107 S**
Peterson et al. (45) **Date of Patent:** **** Nov. 14, 2006**

(54) **TISSUE FASTENING INSTRUMENT**

(75) Inventors: **James A. Peterson**, Edina, MN (US); **David B. Herridge**, Mendota Heights, MN (US); **Chad D. Naegli**, Andover, MN (US); **John L. Shannon, Jr.**, Orono, MN (US); **Christopher J. Sperry**, Plymouth, MN (US); **David M. Stoen**, Mahtomedi, MN (US)

(73) Assignee: **Incisive Surgical, Inc.**, Plymouth, MN (US)

(**) Term: **14 Years**

(21) Appl. No.: **29/202,831**

(22) Filed: **Apr. 5, 2004**

(57) **CLAIM**

We claim the ornamental design for tissue fastening instrument, as shown.

DESCRIPTION

FIG. 1 is a perspective view of a tissue fastening instrument according to an embodiment of the invention;

FIG. 2 is a side view of a tissue fastening instrument according to an embodiment of the invention;

FIG. 3 is a top view of a tissue fastening instrument according to an embodiment of the invention;

FIG. 4 is a bottom view of a tissue fastening instrument according to an embodiment of the invention;

FIG. 5 is a front view of a tissue fastening instrument according to an embodiment of the invention; and,

FIG. 6 is a rear view of a tissue fastening instrument according to an embodiment of the invention.
